UNITED STATES PATENT OFFICE.

OSCAR H. PIEPER AND ALPHONSE F. PIEPER, OF ROCHESTER, NEW YORK.

TIME-CONTROLLED ELECTRIC SWITCH.

Application filed February 14, 1921. Serial No. 444,895.

To all whom it may concern:

Be it known that we, OSCAR H. PIEPER and ALPHONSE F. PIEPER, of Rochester, in the county of Monroe and State of New York, have invented certain new and useful Improvements in Time-Controlled Electric Switches; and we do hereby declare the following to be a full, clear, and exact description of the same, reference being had to the accompanying drawings, forming a part of this specification, and to the reference numerals marked thereon.

This invention has to do with time controlled electric switches and relates more particularly to the variety operating to automatically govern a circuit at the end of a predetermined time period, the chief object of the invention being to provide a practical and convenient switch of the above character adapted for accurately and automatically deenergizing a circuit at the end of a selected period of time. To these and other ends the invention consists in certain improvements and combinations of parts, all as will be hereinafter more fully described, the novel features being pointed out in the claims at the end of the specification.

In the drawings:

Figure 1 is a front view of a time switch embodying the present invention.

Figure 2 is a side view of the same.

Figures 3, 4 and 5 are similar sectional views on the line 3^a—3^a of Figure 1 showing the parts in different positions, with parts broken away in Figure 5.

Figure 6 shows a timing gear train as seen from the line 6^a—6^a in Figure 4.

Figures 7 and 8 are sectional views on the line 7^a—7^a of Figure 3, showing the parts in different positions.

Figure 9 is a fragmentary view on the line 9^a—9^a of Figure 4.

Similar reference numerals throughout the several views indicate the same parts.

The present embodiment of the invention illustrates an adaptation of the latter particularly suited for use in connection with X-ray apparatus such as disclosed in our copending application Serial No. 410,468, filed September 15, 1920, for unitary light projecting apparatus, for accurately deenergizing the circuit of the X-ray tube at the end of an exposure period of selected duration, but it is to be understood that the invention is capable of a wide variety of uses and this embodiment is intended merely

by way of illustration of the principles involved and a preferred practical application of the same, and is capable of various modifications in the details of construction and operation falling within the scope of the claims. In the use referred to it has been found convenient to provide a simple, compact and readily controlled switch of a portable character adapted to be carried in the hand, so that the operator can control the energization of the X-ray tube at any favorable instant while free to assume any position about the apparatus which the work may render advisable. To this end the switch is in the form of a hand instrument connected by extension cords with the apparatus so that it may be carried to any position adjacent the latter.

Referring more particularly to the drawings, and first to Figures 1 and 2, there is shown a casing, in the present instance of aluminum, having a housing portion 10 with a handle portion 11, which portions are preferably threadedly and detachably connected as shown in Figure 7. The front side 12 of the housing portion is preferably removable and held in place as by screws 12^a, and is provided with a zero point 13 adjacent the periphery of a graduated index or dial plate 14 marked with suitable indicia in the present instance indicating seconds of time from 1 to 15. This dial is rotatable to bring the various second graduations selectively into registry with the zero mark by means of a knob 15, to set the timing mechanism as will appear more fully hereafter.

Referring to Figures 3, 4 and 6 for a description of the timing mechanism, there is supported by means of posts 16 secured to the rear side of the housing as by means of screws 17 a pair of spaced supporting plates 18 and 19 between which is carried a timing gear train or clock mechanism of any suitable construction which forms no part of the present invention, however, and requires no detailed description further than to say that this train comprises preferably within a gear 21 a spring motor of a common variety. Gear 21 is rotated to wind the spring to drive the train by means of a pinion 22 fixed with a ratchet wheel 23 on a spindle 24 extending forwardly through the front side of the housing and having adjustably carried thereon the dial 14 and knob 15 previously described. Ratchet wheel 23 is preferably connected by means of a pawl (not

shown) with a gear 25 which serves to drive the train as the spring unwinds, it being apparent that knob 15 may be rotated to wind the spring and bring the second graduations selectively to register with the zero mark, and a retaining means is provided to hold the timing mechanism in such set position until released, as hereafter described. When the time train is released it is driven 10 by the spring motor for a period proportional to the space through which the dial is moved in setting, as indicated by the graduations on the latter, and the dial is returned to zero position.

15 The time train terminates in a spindle 26 carrying a fan governor 27 and the spindle extends through a perforation in the rear supporting plate 18. Fixed on the rear side of plate 18 is a leaf spring 28 carrying 20 adjacent its end a brake finger 29 registering with the end of spindle 26 and adapted to be pressed against the latter by the spring to normally hold the spindle against rotation. Fixed on plate 18 also, between the 25 latter and spring 28, is a second leaf spring 30, and spring 30 extends at its outer end opposite and against the rear end of a bar or plunger 31 sliding in bearing openings in plates 18 and 19 and extending through 30 the forward side of a housing where it is provided with a finger piece or push button 32. It is apparent that by depressing button 32, against the tension of spring 30, the latter is brought to bear against spring 28 35 to move the latter rearwardly and carry its finger 29 out of contact with the time train spindle 26. This mechanism thus forms a restraining device or brake for the time train adapted to normally hold the latter against movement in any position of setting 40 which may be given to it by knob 15 until the button 32 is depressed to release the brake, when the time train is driven by the spring motor and rotates the dial backwardly to initial position.

45 Button 32 is also provided with means for operating a plurality of electrical contacts, hereafter described, simultaneously with the release of the restraining means or brake which sets the time train in operation, such means comprising preferably a pivot pin 33 carried by and extending across an opening in the plunger 31, and on this pin is supported a part or dog 34 arranged to engage during rearward movement of the plunger with one end of a lever 35 pivoted at 36 on lugs on plate 19. The other end 37 of this lever bears against an insulating surface on a spring clip 38 of electrically conducting material fixed as by means of screws 38^a to a block 39 of insulating material fixed in turn by means of screws 40 on plate 19. Clip 38 carries on its under side a contact 41 adapted, upon depression of the clip, 50 by the lever, to engage a contact 42 on a

55 spring clip 43 of conducting material fixed as by means of screws 44 on the block 39. Clip 43 carries a contact 45 and continued movement of the lever and of clip 38 moves clip 43 to engage its contact 45 with the end 60 of a contact screw 46 carried in block 39. Contacts 41 and 42 are thus closed before contacts 45 and 46 and vice versa upon opening the contacts, for the purpose of making and breaking the circuit through a suitable resistance connected with contact 42 as well understood in the art. Screws 38^a, 44 and 46 form binding posts for the connections with the circuits to be governed, the contacts being shown in closed and open positions 65 in Figures 4 and 3, respectively, as adjusted by movement of lever 35. The latter has an extension 47 for engagement with plate 19 to limit its movement under actuation of the contact springs, and it is apparent that with the lever in such position, Figure 5, with the contacts in open relation, depression of button 32 by means of dog 34 swings lever 35 to the position shown in Figure 3 70 and holds the contacts closed as long as the button is depressed. Dog 34 has a tail portion 48 normally held against plunger 31 by a spring 49 between the latter and an extension 50 on the dog, for holding the dog in position to engage lever 35. Means are provided, however, for automatically swinging dog 34 on its pivot at the end of the selected time period so that it disengages lever 35, permitting the latter to be moved by the contact springs and the contacts to be moved to open position, thus breaking 75 the circuit.

80 The means for thus moving or tripping dog 34 to allow the contacts to be opened comprises preferably an element or arm 51 provided with a kerf 52 embracing the setting spindle 24 of the time train for adjustably clamping the arm on the spindle as by means of a screw 53. The arm is formed with a cam surface 54 which, at the end of 85 the time period during which the gear train rotates, is brought into engagement with extension 50 of dog 34, moving or tripping the latter to release the contact lever 35 and allow the contacts to open. A stop 55 is 90 carried by plate 19 in position to arrest the movement of arm 51 and of the gear train when cam 54 has tripped the dog. Sufficient tension is initially placed on the gear train motor spring to cause dial 14 to be rotated through the space represented by a unit graduation thereon during one second of 95 time, and arm 51 is then clamped on spindle 24 in engagement with stop 55. Dial 14 is then adjusted on spindle 24 with its zero 100 mark opposite the fixed zero on the housing and the instrument is then ready for use.

105 In operation, as indicated by the above description, knob 15 is rotated through a space corresponding to the number of sec- 110

- onds for which it is desired to energize the X-ray tube circuit, and the brake means holds the knob and time train in such position of setting. When the preparations for 5 the exposure are completed the operator presses the finger piece or button 32 which simultaneously starts the time train and closes the contacts. The time train rotates through the desired period of time at the end 10 of which period the contacts are automatically opened by the tripping device described, so that the desired time period is accurately and automatically measured and the circuit opened without requiring further 15 attention on the part of the operator than the initial setting of the time train and the application of pressure to the button. It is to be understood of course that button 32 is held depressed by the operator's finger until 20 the timing mechanism has opened the contacts at the end of the selected period, although of course if desired the button might be depressed and released one or more times during the timing period where, for 25 example, the exposure is during the period for some reason interrupted. Ordinarily however the button is depressed and held depressed until the time train opens the contacts.
- 30 The invention provides an exceedingly convenient time switch of a light, compact and portable character adapted to be carried in the hand of the operator. The time train is quickly and readily set to correspond with 35 the desired duration of the exposure with little chance for error, and the operator may then energize the apparatus and accurately effect the desired exposure at a favorable instant from any position he may wish to 40 assume about the apparatus by a simple pressure of the button. The construction is practical, compact and reliable and affords a conveniently useful and attractive instrument.
- 45 We claim as our invention:
1. In a time controlled electric switch, a pair of contacts, a timing gear train, a motor for driving said train, adjustable means for setting said train to operate through a selected period of time, a brake for said train, controlling means for moving said contacts to one position and releasing said brake to start said train, and a device actuated by said timing train to effect movement of said contacts to another position at the end of said selected period.
  2. In a time controlled electric switch, a plurality of contacts, a timing gear train, a motor for driving said train, adjustable means for preliminarily setting said train to operate through a selected period of time, a brake for holding said train in set position, controlling means connected by movable parts with said contacts to move the latter to one position and with said brake to release the same and start said train, and a device actuated by said timing train for disestablishing said connection between the controlling means and contacts to permit movement of the latter to another position. 70
  3. In a time controlled electric switch, a plurality of contacts, a timing gear train, a motor for driving said train, adjustable means for preliminarily setting said train to operate through a selected period of time, a brake for holding said train in set position, a finger piece connected with said contacts and brake to move the contacts to one position and release the brake to start said train, and a device actuated by said train for disestablishing said connection between said finger piece and contacts to permit movement of the latter to another position at the end of said selected period. 75
  4. In a time controlled electric switch, a plurality of normally open spring actuated contacts, a timing gear train, a motor for driving said train, adjustable means for preliminarily setting said train to operate through a selected period of time, a brake for holding said train in set position, controlling means connected by movable parts with said contacts and brake to simultaneously close said contacts and release said brake, and a trip device actuated by said timing train to disconnect said controlling means and contacts and permit opening of the latter at the end of said selected period. 80
  5. In a time controlled electric switch, a plurality of normally open spring actuated contacts, a timing gear train, a motor for driving said train, adjustable means comprising a graduated dial for preliminarily setting said train to operate through a selected period of time, retaining means for holding said train in set position, a push button connected with said contacts and retaining means to simultaneously close the contacts and release the restraining means, and a device actuated by said timing train to disconnect said push button and contacts to permit opening of the latter at the end of said selected period. 85
  6. In a time controlled electric switch, a plurality of spring actuated contacts, a spring actuated gear train, setting means for winding said train spring and setting said train for movement through a selected time period, retaining means for holding said train in set position, a finger piece for releasing said retaining means having also a part movably carried thereon for closing said contacts, and a device actuated by said train for moving said part to disconnect said finger piece and contacts and permit opening of the latter at the end of said selected period. 90
  7. In a time controlled electric switch, a plurality of contacts, a timing gear train, a motor for driving the latter, adjustable 95
  - 100
  - 105
  - 110
  - 115
  - 120
  - 125
  - 130

means for setting said train for operation through a selected time period, retaining means for holding said train in set position, a finger piece movable to release said retaining means, a dog pivotally carried on said finger piece having means for moving said contacts to one position during said movement of the finger piece, and a tripping element actuated by said timing train to trip 10 said dog and effect movement of said contacts to another position at the end of said selected period.

8. In a time controlled electric switch, a plurality of contacts, a timing gear train, a 15 motor for driving the latter, adjustable means for setting said train for operation through a selected time period, spring actuated retaining means normally holding said train against movement, a finger piece movable to release said retaining means to start 20 said train, a dog movably carried by said finger piece, a lever actuated by said dog during said movement of the finger piece for moving said contacts to one position, and 25 a tripping element actuated by said train to disengage said dog and lever and effect movement of said contacts to another position at the end of said time period.

9. In a time controlled electric switch, a 30 plurality of spring actuated contacts, a timing gear train, a motor for driving the latter, adjustable means for setting said train for operation through a selected time period, spring actuated retaining means for holding 35 said train against movement, a plunger movable to release said retaining means and having a dog pivoted thereon, a pivoted lever in the path of movement of said dog during 40 said movement of the plunger for closing said contacts, and an element actuated by said train to disengage said dog and lever to permit said contacts to open at the end of said time period.

10. A portable time switch adapted to be 45 carried in the hand comprising a casing having a handle, spring actuated contacts in said casing provided with means for connecting the same in a circuit, a timing gear train in the casing provided with a motor, 50 adjustable means extending through said casing and provided with an index for setting said train to operate through a selected period of time, restraining means for holding said train in set position, a finger piece 55 extending through the casing having a connection with said restraining means and contacts to simultaneously release the former and close the latter, and a tripping device actuated by said train for automatically 60 disconnecting said finger piece and contacts to permit opening of the latter at the end of said selected time period.

11. In a device of the class described, a 65 self opening electric switch, a push-plunger comprising parts adapted to cooperate unitarily for manually closing and controlling said switch, said parts being also relatively adjustable to release said switch, and time operated means for effecting said relative adjustment of said parts at the end of a 70 measured period to release the switch for opening movement.

12. In a device of the class described, an 75 electric circuit controlling switch, a member for manually and automatically controlling said switch, push button means for manually actuating said member, said member and push button means being adjustably connected for cooperation unitarily to control the switch and also to permit independent movement of said member, and time mechanism for moving said member independently of said button, means to effect automatic control of said switch at the end of a measured period.

13. In a device of the class described, a 80 self opening electric switch, clock mechanism for timing the duration of closure of said switch, a trip member for closing said switch, a push member cooperating with said trip member for manually closing said switch, said trip member being adjustably connected to said push member, and means 85 operated by said clock mechanism for adjusting said trip member relative to the push member while the push member is depressed to close the switch for releasing the switch and effecting an automatic opening thereof at the end of a predetermined period.

14. In a device of the class described, an 90 electric circuit controlling switch, a rewind time setting clock mechanism for timed switch control to break the circuit at the end of a predetermined measured period, a member comprising adjustably connected sections 95 adapted to cooperate unitarily for clock operation control and switch actuation, and means actuated by said clock mechanism for adjusting the sections of said member to effect automatic switch opening while said sectional member is manually held in switch closing position.

15. A self-opening electric switch, a sectional plunger, means for adjustably connecting said sections together, said plunger being manually operable to close said switch and hold it closed when the sections are connected together in one adjustment, and means for causing an automatic variably timed adjustment of said sections to permit opening of said switch while said plunger is in its switch closing position.
